(57) **CLAIM**

The ornamental design for a remote control, as shown and described.

DESCRIPTION

FIG. 1 is a front perspective view of a remote control, showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of portion '8' in FIG. 1; and,

FIG. 9 is an enlarged view of portion '9' in FIG. 7.

The broken lines in the drawings illustrate portions of the remote control that form no part of the claimed design. The dash-dash broken lines encircling portions of the remote control in FIGS. 1, and 7-9 are included to show a partially enlarged view only and form no part of the claimed design.
